UNITED STATES PATENT OFFICE.

WILLIAM C. BROWN, OF SYRACUSE, NEW YORK.

PUMP.

1,366,713.

Specification of Letters Patent. Patented Jan. 25, 1921.

Application filed December 16, 1915. Serial No. 67,137.

To all whom it may concern:

Be it known that I, WILLIAM C. BROWN, a citizen of the United States, residing at Syracuse, in the county of Onondaga, State 5 of New York, have invented new and useful Pumps, of which the following is a specification.

My invention relates to improvements in pumps. The object is to utilize the momentum of a weight connected with the power piston and the pump piston or plunger, in which connection the weight of the moving parts is used for the purpose of storing energy during the early part of the power 10 stroke and giving off said stored energy toward the end of said stroke. In vertical single acting machines I also utilize gravity in returning the parts to original position, and compressing the expandable medium in 15 the power cylinder.

The invention is especially adapted to overcoming the difficulty in the practical operation of a steam pump using steam expansively and using a reciprocating weight 25 or heavy parts for storing the energy at the beginning of the stroke and getting it back at the end of the stroke. The means for overcoming this difficulty are three.

1. A single acting pump in which the 30 length of the upward travel is unimportant and the length of the downward travel is kept fairly uniform on account of the uniform conditions of gravity of a given weight compressing a given amount of steam at a 35 substantially constant initial pressure.

2. The use of a una-flow engine in which the exhaust valve is closed about the time the steam piston starts on its return stroke, thereby compressing practically the whole 40 cylinder full of steam and running the compression up so high at the end of the stroke that small differences in the travel make great differences in the pressure and consequently slight differences in the length of 45 stroke.

3. A retarded valve action which permits the piston to travel after the valve mechanism has moved to a point where the valve will be thrown.

50 While I show all three methods used in combination, it is obvious that either of these three methods may be used separately, or any two may be used in combination.

In a steam pump using steam expansively, 55 in order to obtain economical results from the steam, a condition exists of a power

piston against which there is a variable pressure driving a water piston or plunger against which there is a constant resistance, so that it is necessary by some means to 60 store the excess of energy during the first part of the stroke, when the pressure against the power piston exceeds the resistance against the water piston, and to give off this energy at the latter part of the stroke when 65 the steam pressure has fallen, due to the cut off and consequent expansion, so that the pressure against the power piston is less than the resistance against the water plunger. This is ordinarily accomplished by 70 means of a fly wheel requiring not only the fly wheel but its shaft, with its bearings, cranks, connecting rods, etc. It is possible to accomplish this result by means of a reciprocating weight. Difficulties in the past 75 have been encountered in constructing a machine using a reciprocating weight which would operate successfully from a mechanical standpoint.

The object of the present invention is to 80 overcome these difficulties and permit of a satisfactory commercial machine using a reciprocating weight and thereby getting away from the fly wheel and its necessary complications.

Referring to the drawings which illustrate merely by way of example, suitable embodiments of my invention—

Figure 1 is a vertical section of a single 90 acting pump.

Fig. 2 is a similar view of a pump having a una-flow double acting power cylinder, with a differential plunger connected with the power piston.

Figs. 3 and 4 are details of the valve actuating mechanism.

Similar numerals refer to similar parts throughout the several views.

Referring to Fig. 1, the power cylinder 5 is a single acting una-flow steam cylinder 100 having a jacket 6 at the live steam intake end of the cylinder. Live steam is introduced into this jacket through steam supply pipe 7 and circulates through the jacket chamber 6 before delivering through valve 105 8 to the cylinder 5.

The steam discharges or exhausts through ports 9 which are controlled by the piston 10, which uncovers said ports 9 at the end of the power stroke.

Ports 9 deliver to an exhaust belt 11 which in turn delivers to the exhaust pipe 12.

Near the top of the cylinder body 5 are provided ports 13 communicating with the exhaust belt 11. Through these ports exhaust steam may be drawn in and expelled from the cylinder by the piston reciprocation. These ports 13 are so disposed that the cold end of the piston will overrun them near the end of the power stroke and close the same. This results in trapping an elastic cushion in the top of the cylinder and compressing the same, thus affording a cushioning stop for the end of the upstroke or power stroke and this cushion is adapted to react in accelerating the return stroke.

15 The vent 14 controlled by needle valve 15 forms adjustable means for regulating the effectiveness of the said cushion.

In all pumps using reciprocated weights for storing energy there is nothing which 20 mechanically regulates the length of stroke to take the place of the throw of the crank where a fly-wheel is used. The length of stroke therefore is liable to vary with variations in the steam pressure and variations in 25 the water pressure with which almost every pump has to contend. In order to overcome this difficulty this machine is made single acting, the power stroke is upward, there being no work done by the pump on the 30 down-stroke and consequently there is no necessity for operating an inlet steam valve to produce the down stroke. Variations of steam and water pressures tend to vary the unstroke but, so long as the piston travels 35 far enough to open the exhaust, the mechanical operation of the machine is not affected by the length of the stroke. It can be readily understood that it would be perfectly feasible to impart a velocity to the upward 40 moving parts and let them come to rest after the exhaust port has become opened by the retardation due to gravity, by simply making the cylinder sufficiently long to cover ordinary cases. As a break in the discharge 45 pipe might entirely relieve the load from the plunger the cylinder would have to be quite long to guard against this contingency, and therefore the air cushion or dash-pot is provided for the top of the piston to stop the 50 working parts on the upstroke in case, for any reason, an unusual amount of energy has been stored in the moving weight.

To the piston 10 is connected, by the piston rod 16, the weight 17, and by the piston 55 rod 18, the plunger or pump piston 19. The plunger 19 reciprocates in the cylinder 20 inclosed within the chambered body 21. This chambered body 21 connects at its lower end with the supply pipe 22 and at its upper 60 end with the discharge pipe 23. The cylinder 20 and the non-return valves 24 and 25 divide the chambered body 21 into three compartments as follows:—compartment 26 connected with the supply pipe 22, compartment 65 27 connected with the cylinder 20 and

compartment 28 connected with the discharge pipe 23.

Compartment 26 also forms a suction air chamber in connection with suction pipe 22.

As the work is intermittent, a discharge 70 air chamber will be desirable, which can be connected with the discharge pipe 23 in any suitable way, as for example the air chamber 58, see Fig. 2.

It will be noted that cylinder 20 is open 75 at both ends.

It is desirable that the down-stroke should be practically uniform as the steam admission valve is opened by a mechanism attached directly to the moving parts, but unless some means were provided to insure a uniformity in the length of the down-stroke, a condition might exist whereby the stroke would not be sufficiently long to open the steam valve and the pump would stop. In 85 this machine there is no work done in the down-stroke, excepting the compression of the steam entrapped in the cylinder after exhaust has taken place, and as the amount of steam entrapped is a substantially constant amount and the gravity action of the weight of the parts a constant force, the compression will be practically constant and the point of coming to rest practically the same.

It may perhaps be impossible in every case to keep this down-stroke exact as to length, due to variation of friction of the parts, and therefore it is desirable to provide some means which will permit of a slight variation without stopping the pump by cause of the stroke not being of sufficient length to open the steam admission valve. This result is accomplished by imparting to the valve operating mechanism a slightly 105 retarding action so that there will be a certain interval of time after the valve mechanism has moved to a point where the valve will be opened, before the valve is actually opened. In this way the valve mechanism 110 can be set so that it will be operated shortly before the piston comes to the desired end of its stroke and the piston will continue to travel and reach the desired point at the time the valve is opened to start the return 115 stroke. If this is done it can readily be seen that if on account of extra friction, due to poor lubrication, or any other cause, the piston does not drop to the desired point, the valve will still be opened, even if a little 120 late, and the machine will continue to operate.

The steam admission valve 8 is operated by the following means. The lever 29 is pivoted at 30 to the fixed housing 31. This 125 lever is connected by the link 32 to a collar 33 on piston rod 16, and is also connected at 34 to the spindle 35 which is comprised in the valve actuating mechanism.

Referring to Figs. 3 and 4 the port 66 130

communicates with the live steam space in the cylinder head 6 and serves to establish communication through the recess 67 about the spindle 35 with the space 68 behind the 5 piston valve 8 when the spindle 35 is in the required position. The spindle 35 is moved into the position, shown in Fig. 4, when the piston 10 reaches the point where cut off is desired, and the pressure thus established 10 behind piston valve 8 causes the valve 8 to move into the position closing port 69. Upon the down stroke of piston 10 and the other reciprocating parts the spindle is shifted as above described into the position 15 shown in Fig. 3, establishing communication between exhaust channel 70, pipe 70', and exhaust belt 11, and cutting off communication with port 66, thus relieving pressure behind piston valve 8. Piston 8, now being subject 20 to the pressure of live steam upon its other side, and also to the pressure of the steam trapped and compressed beneath the piston 10, will open said port 69. The rapidity of said opening movement will depend upon 25 the degree of opening in the exhaust channel 70 which is controlled by the adjustable needle valve 71.

Operation: Upon admission of live steam into the power cylinder beneath the power 30 piston, the piston is driven upwardly, causing the upward movement of weight 17 and of plunger 19.

When the resistance of the plunger and of the weight, due to the combined action of 35 the elastic cushion compressed at the top of the cylinder and to gravity, overcomes the gradually falling pressure in the steam cylinder and the stored energy in the weight, the parts will come to rest after the exhaust 40 ports have been opened, permitting the steam to be exhausted from the cylinder. It is not essential to the successful operation of the machine that the parts shall stop immediately upon opening the exhaust ports, 45 therefore the action is not so sensitive as to require accurate regulation.

After the parts have come to rest they will return to their original position by the reaction of the elastic cushion and by gravity, 50 compressing the steam entrapped below the piston, after the piston has closed the exhaust port.

Upon the power stroke of the piston 10, which causes the upstroke of plunger 19, 55 liquid is drawn into compartment 27 through valve 24 and into the lower end of cylinder 20. Liquid is also delivered from the top of cylinder 20 above the plunger, and consequently through discharge pipe 23. 60 Upon the down stroke or gravity stroke of plunger 19, liquid is discharged from compartment 27 through valve 25 into compartment 28, as the liquid is propelled from the lower end of cylinder 20. At the same time 65 liquid under pressure at its head follows

and exerts pressure upon the upper side of plunger 19, so that the pressures above and below the plunger are balanced, and there is little or no work done by the plunger in said gravity stroke, while in the power stroke the 70 plunger 19 operates against suction pressure and also against head, and practically all the work is done on this stroke.

In Fig. 2, I show a double acting-unaf- 75 flow steam power cylinder 36 having steam jackets 37 and 38 at each end and live steam inlet valves 39 and 40 located in said jacks- 80 ets. The exhaust ports 41 are located in the middle of the cylinder and discharge to the exhaust belt 42 which in turn discharges 85 into the exhaust pipe 43. The power piston 44 is adapted to overrun the exhaust ports and open the same for the exhaust of steam at the end of each stroke. The power pis- 90 ton 44 is connected by the piston rod 45 with the weight 46 which in turn is connected with the differential plungers 47 and 48. Plunger 48 operates in the cylinder 49 which is open at both ends and is suitably sup- 95 ported in the compartments 50 and 51 of the chambered body 52. This chambered body 52 is also provided with the compartment 53 connected with the liquid supply port 54 and with the compartment 55 con- 100 nected with the discharge port 56. Com- 105 partments 53 and 55 are also provided with the air chambers 57 and 58 respectively. Non-return valves 59 are provided between compartment 53 and compartments 51 and 50 while non-return valves 60 are provided between compartment 50 and 51 and compartment 55. The valves 39 and 40 of the power cylinder are controlled by a suitable cam rod 61 operated by the lever 62 pivoted at 63 and operatively connected as at 64 with 105 the piston rod 45.

It will be understood that with a double 110 acting power cylinder the plunger and weight may be operated either horizontally or vertically. Where horizontally the mo- 115 mentum alone of the weight is utilized in each direction of its movement. When op- erated vertically as shown in the present ex- ample, momentum and gravity of the weight are used in the down stroke, while mo- 120 mentum only is utilized in the upstroke. For this reason, a differential plunger is used to balance the weight so that the effect will be the same on both the up and down stroke.

In operation, starting for example with the piston in the lower position upon admit- 125 ting steam through valve 40 the piston is carried upwardly until the exhaust ports 41 are uncovered by said piston permitting the exhaust of the steam therethrough, while a certain amount of exhaust steam is en- 130 trapped and compressed above the piston in the upper part of the cylinder thus cushioning the end of the upstroke. The excessive

energy at the beginning of the stroke before cut-off and during expansion after cut-off is absorbed by the weight 46 and the other moving parts, which energy is given back by the momentum of the moving parts thus completing the stroke and compressing the exhaust steam above the piston 44. When the piston reaches the top of the stroke the steam valve 39 will be opened 5 causing the piston to start downward in the same manner as the upstroke, thus completing the cycle. Upon the upstroke of plungers 47 and 48 liquid is drawn through non-return valves 59 into compartment 51 and 10 is discharged from compartment 50 through non-return valve 60 into the compartment 55 and thence out through discharge port 56. Upon the downstroke of plungers 47 and 48 liquid is introduced through non- 15 return valves 59 into compartment 50 and liquid at the same time is discharged from compartment 51 through non-return valve 60 into compartment 55. It will be noted however that on the down stroke liquid representing the entire displacement of plunger 48 will be discharged from compartment 51 while on the upstroke the liquid displaced will only be that affected by the area of plunger 48 less the area of plunger 47 so 20 as to compensate for the gravity force opposed to the upstroke.

Una-flow engines are especially adapted to my purpose in that the compression pressure rises so rapidly at the end of the stroke, 35 that slight differences in length of stroke cause great differences in pressure.

Single acting pistons permit a great variation of the stroke in one direction, which does no harm, and slight variations in the 40 other direction due to constant conditions.

While the present invention is especially adapted to steam operated pumps, it will be understood that compressed air may be used as the power medium with corresponding 45 results.

What I claim is:—

1. In a pump, the combination of a pump-chamber and piston or plunger operating therein, a steam power cylinder and 50 piston operating therein, means for establishing operative relationship between said pistons, heavy parts moving with said power piston capable of reciprocation with variable stroke adapted to store energy during the early part of the power stroke and to give out energy during the latter part thereof, said power piston adapted to close 55

the exhaust port at the beginning of the return stroke and operating by gravity in connection with the heavy parts to compress 60 practically the whole cylinder full of steam to cause a high compression thereof at the end of the return stroke, and operating on the power stroke only to perform all the work of pumping both on the suction and 65 delivery side.

2. In a pump, the combination of a steam power cylinder, a power piston operating therein with a variable stroke, heavy parts connected with the piston as means for utilizing momentum to absorb energy during the early part of the power stroke, and to give out energy during the latter part thereof, whereby the steam may act expansively, the cylinder provided with exhaust ports 70 adapted to be opened near the end of the power stroke and to be closed at such point on the return stroke that a large part of the expanded steam is trapped by the piston and highly compressed at the end of the 75 return stroke, said cylinder also provided with a steam admission valve and controlling mechanism therefor initially actuated by the piston movement prior to the end of its normal return stroke whereby the valve 80 is opened a substantial period after said initial actuation, for the purpose of insuring said valve opening, in case of a less than normal return stroke.

3. In a pump, the combination of a pump-chamber and piston or plunger operating therein, a una-flow single acting steam power cylinder and piston operating therein, means for establishing operative relationship between said pistons, heavy parts moving with said power piston capable of reciprocation with variable stroke adapted to store energy during the early part of the power stroke and to give out energy during the latter part thereof, said power piston 95 adapted to close the exhaust port at the beginning of the return stroke and operating by gravity in connection with the heavy parts to compress practically the whole cylinder full of steam to cause a high compression thereof at the end of the return stroke, and operating on the power stroke only to perform all the work of pumping both on the suction and delivery side.
